United States Patent

Des. 235,579
Patented June 24, 1975

235,579

TYPEWRITER

Alejandro De Tomaso and Thom Tjaarda, Turin, Italy,
assignors to SCM Corporation, New York, N.Y.

Filed Oct. 25, 1972, Ser. No. 300,534

Term of patent 14 years

Int. Cl. D18—01

U.S. Cl. D64—11 A

FIG 1

FIG 2

FIG. 1 is a front perspective view of a typewriter showing our new design;

FIG. 2 is a top plan view;

FIG. 3 is a right side elevational view;

FIG. 4 is a back elevational view;

FIG. 5 is a left side elevational view; and

FIG. 6 is a front elevational view.

The typebar guide and typebars are conventional and have been omitted for ease of illustration.

We claim:

The ornamental design for a typewriter, substantially as shown and described.
